(57) CLAIM

The ornamental design for a shotgun holster, as shown and described.

DESCRIPTION

FIG. 1 is a perspective view of a shotgun holster showing my new design, wherein the broken lines form no part of the claimed design;

FIG. 2 is a front view of the same, wherein the broken lines form no part of the claimed design;

FIG. 3 is a rear view of the same, wherein the broken lines form no part of the claimed design;

FIG. 4 is a right side view of the same;

FIG. 5 is a left side view of the same;

FIG. 6 is a top view of the same;

FIG. 7 is a bottom view of the same;

FIG. 8 is a perspective view of the shotgun holster shown attached to the belt of a wearer;

FIG. 9 is another perspective view of the shotgun holster shown in use;

FIG. 10 is an enlarged view of the shotgun holster showing the trigger guard and operating handle in abutment with the holster; and,

FIG. 11 is an additional perspective view of the shotgun holster.

The broken line showing of environment in the drawings is for illustrative purposes only and forms no part of the claimed design.
